UNITED STATES PATENT OFFICE.

ALBERT ROYE, OF COLUMBIA, PENNSYLVANIA.

DESIGN FOR A LIGHT-CUT GLASS TUMBLER, STEM-WARE, JUG, BOWL, OR VASE.

48,831.

Specification for Design.

Patented Apr. 4, 1916.

Application filed December 27, 1915. Serial No. 68,961. Term of patent 3½ years.

To all whom it may concern:

Be it known that I, ALBERT ROYE, a citizen of the United States, residing at Columbia, Lancaster county, Pennsylvania, have invented a new, original, and ornamental Design for a Light-Cut Glass Tumbler, Stem-Ware, Jug, Bowl, or Vase, of which the following is a specification, reference being had to the accompanying drawing, forming a part thereof, and in which—

Figure 1 is a view in elevation of a tum-

bler illustrating my new design, and Fig. 2 is a similar view of the opposite side thereof.

I claim:—

The ornamental design for a light-cut glass tumbler, stem-ware, jug, bowl, or vase, as shown.

ALBERT ROYE.
